REINFORCED FLEXIBLE CONVEYER STRIP

Charles N. Bebinger, New Philadelphia, Ohio, assignor to Joy Manufacturing Company, Pittsburgh, Pa., a corporation of Pennsylvania

Application May 1, 1951, Serial No. 224,023

4 Claims. (Cl. 198—1)

1

My invention relates to flexible shaker conveyors, and more particularly to the flexible conveyor elements proper of such conveyors.

Flexible shaker conveyors—shaker conveyors which utilize a longitudinally reciprocated single strand, metallic strip, drawn many times a minute in one—the discharge—direction in a period which is materially greater than one-half of the duration of a complete reciprocatory cycle and, between each such movement and the next, drawn in the opposite direction in a period which is materially less than one-half of such duration—are a desirable arrangement for moving material such as—but without limitation thereto—coal from one location to another. Such conveyors employ as the material supporting and moving strips bands of steel strip on the order of 30 inches to 42 inches wide, but it is to be understood that these dimensions, and any others not otherwise stated, are to be considered as illustrative, and not limiting. A desirable thickness for the strips is on the order of a few hundredths of an inch, and a thickness of .030 inch has been found satisfactorily to meet requirements under many conditions. Thicknesses up to .040" or .050" may be employed if the material to be conveyed, or the load or stresses on the belt so dictate, and it is to be understood that these figures are illustrative and not limiting. Such strips are supported and guided and troughed by troughing idlers, and accordingly need the flexibility crosswise which they possess. They are made in units of considerable length, and their working length varies as the point of material reception moves further away from the point of material delivery, and accordingly storage for the inactive portions of the strip is necessary. This is desirably accomplished by coiling the strip on a reel and "paying out" strip as the need for increased working length arises; and oscillation of the reel on its own axis, bodily arcuate movement thereof, rectilinear reciprocation thereof, and traction on the strip at a point between the reel and the so-called free end of the strip may, any of them, be utilized in the effecting of traction of the strip in one direction. There is, accordingly, need for the longitudinal flexibility which characterizes a thin steel strip. In addition, the strip changes its transverse conformation in use, being desirably wound flat on the reel, but being troughed throughout most of its length, and as close up to the reel as possible. As is the case also with endless belts used for conveying purposes, the edges of the strip come in for maximum wear and stressing, and are,

2

because of the change in the transverse conformation of the strip subjected to particularly severe tensile stresses. It is therefore desirable to provide edge reinforcement for the strip, and this can be done in various ways—as, for example, by rolling the strip with thickened edges, by sweating onto each edge a reinforcing strip, as with silver solder, or by spot welding a U-shaped strip over either edge. With the reinforcement of the edges the provision of a corresponding thickening intermediate the edges and preferably at the longitudinal central zone of the strip becomes desirable, in order that the strip may wind well on a reel; and the strip may be rolled with a central thickening, or may have a thickening strip or strips, sweated or spot welded along its longitudinal central portion, depending on the nature of the edge reinforcement. A plurality of spaced intermediate thickenings, instead of a single central one, may be employed.

In a preferred embodiment the strip may have its edges and a narrow width along its longitudinal center line rolled thicker than—perhaps twice as thick as—the thickness at other points transversely of it, and these thickenings may desirably be at one face of the strip—preferably at the face of the strip which in use will constitute its upper—material supporting—surface.

In the accompanying drawings, in which I have shown for purposes of illustration a preferred embodiment which the invention may assume in practice:

Fig. 1 is a plan view of a single strand conveyor strip in which the invention is incorporated.

Fig. 2 is a transverse section, on an enlarged scale, of the strip of Fig. 1, shown curved transversely, as it would normally be at points remote from an associated reel, by the pressure of the load and the manner of support by the troughing idlers which support and guide it as it carries and conveys a load.

Fig. 3 is a view on a different scale, partially in elevation and partially broken away to show the manner of strip storage, showing a reel with a strip of the construction illustrated in Figs. 1 and 2 wound and stored upon it.

Fig. 4 is a transverse section through the reel and strip of Fig. 3, taken upon the plane of the line 4—4 of Fig. 3.

Referring to the drawings, and first to Figs. 1 and 2, there will be noted at 11 a single strand shaker conveyor strip. This may be of steel—chrome nickel stainless is satisfactory—of any convenient length, on the order of .030 inch thick

(but note what is said above as to thickness throughout most of its width), plane from edge to edge at its lower side when flat, having its edges thickened at its upper side, as at 12, 12, for a width of an inch or more, and with a relatively narrow, one inch or more wide, central thickened or reinforced portion 13, of a thickness at least substantially the same as the reinforced edges 12, 12 and with this reinforcement also formed at the upper side of the strip. The strip has between the center reinforcement 13 and each of the edge reinforcements portions 14, 14, desirably of substantially uniform thickness. The thicker reinforced portions merge gradually, as at 15—i. e. taper into, the portions 14, 14. The strip 11 is shown in Fig. 2 as upwardly concave, and as conforming to a portion of a surface of revolution at its lower side, as such a curving would readily be imposed on the strip by the coaction of the load with underlying arcuately arranged supporting idlers, and will permit the flattening of the strip as it is wound on a reel as shown in Fig. 3. It will be clear that the strip could be conformed in use to other transverse shapes, as illustrated in my application, Serial No. 201,891, filed December 21, 1950, but it may be said in general that the avoidance of a definite line or lines of flexure extending lengthwise of the strip will aid in the prolongation of life of the latter and permit smooth reeling thereof with smaller winding forces.

As earlier noted, it is desirable, as a practical preposition, that the portions of the strip not actively in use shall be reeled up, and Figs. 3 and 4 show a reel 20, having a spool or drum portion 21 and end flanges or heads 22. The drum or spool portion 21 is cylindrical and the strip is shown wound with its flat (unthickened) side "in," i. e. towards the axis of the reel. It will be noted that as the strip is wound, the thickened portions 12, 13 and 12 of each wrap engage the smooth side of the next outer convolution, beneath the reinforcing thickenings of the same. The provision of the central thickened strip prevents any sagging of the central section of the strip and insures winding and storage of the latter in such a manner that the paying off—or winding in—of, say, one wrap will result in equal elongation—or shortening—of the paid out portion of the strip by equal amounts at each edge and at its center.

Fig. 4 may be noted at the point indicated by the reference character 25, where the transition of the strip from a trough-like to a transversely straight conformation—or vice versa—is clearly seen.

By reason of this invention, a flexible strip for a flexible shaker conveyor is provided which will be materially more durable, be wound up and paid out—even after extended use—in a more desirable manner, and serve its purposes without serious impediment to its effective use by reason of the changes in construction made to secure the advantages which it provides.

While there is in this application specifically

described one form which the invention may assume in practice, it will be understood that this form of the same is shown for purposes of illustration, and that the invention may be modified and embodied in various other forms without departing from its spirit or the scope of the appended claims.

What I claim is:

1. A thin, flexible metallic conveyor strip of uniform width and having at its opposite edges, reinforcing the same, and midway between its edges, relatively narrow portions of greater thickness than the portions intermediate said thicker portions are at any points therein, said relatively narrow portions having their overall thickness much less than their width and said strip, except at said relatively narrow portions of greater thickness, of a substantially uniform thinness.

2. A flexible metallic conveyor strip of uniform width and of uniform thickness throughout most of its width and having at its opposite edges relatively narrow portions of increased thickness having their overall thickness much less than their width and said strip further having between said relatively narrow portions increased thickening of corresponding amount to preclude sagging of the portion of the strip between said relatively narrow portions upon winding on a reel.

3. A flexible metallic conveyor strip of uniform width and of uniform thickness throughout most of its width and having at its opposite edges relatively narrow portions of increased thickness having their overall thickness much less than their width and said strip further having between said relatively narrow portions increased thickening of corresponding amount and generally corresponding width to preclude sagging of the portion of the strip between said relatively narrow portions upon winding on a reel.

4. A thin, flexible metallic conveyor strip of uniform width and of uniform thickness throughout most of its width and having at its opposite edges relatively narrow portions of increased thickness and further having between said relatively narrow edge portions at least one further relatively narrow portion of increased thickness to preclude sagging of the central portion of the strip upon winding on a reel, said strip other than at said edge portions and at said at least one relatively narrow portion of increased thickness being materially thinner than said portions and said thinner portions being much wider than the thicker ones and said thicker ones much wider than their own overall thickness.

CHARLES N. BEBINGER.
